US00D755193S

(12) **United States Design Patent**
Sun et al.

(10) **Patent No.:** US D755,193 S
(45) **Date of Patent:** ** May 3, 2016

(54) **DISPLAY SCREEN WITH GRAPHICAL USER INTERFACE**

(71) **Applicant:** **Tencent Technology (Shenzhen) Company Limited**, Shenzhen, Guangdong (CN)

(72) **Inventors:** **Xiao Sun**, Guangdong (CN); **Cuiong Ma**, Guangdong (CN); **Shaomian Yao**, Guangdong (CN)

(73) **Assignee:** **Tencent Technology (Shenzhen) Company Limited** (CN)

(**) **Term:** **14 Years**

(21) **Appl. No.:** **29/475,253**

(22) **Filed:** **Dec. 2, 2013**

(51) **LOC (10) Cl.** **14-04**

(52) **U.S. Cl.**

USPC **D14/485**

(58) **Field of Classification Search**

USPC D14/485-495
CPC G06F 3/048; G06F 3/0481; G06F 3/0482; G06F 3/04817

(57) **CLAIM**

The ornamental design for the display screen with graphical user interface, as shown and described.

DESCRIPTION

The FIGURE is a front view of the display screen with graphical user interface showing our new design.

The broken line showing of a portion of a display screen in the FIGURE forms no part of the claimed design. The broken line showing of text and portions of the graphical user interface in the FIGURE represents environmental subject matter and forms no part of the claimed design.

1 Claim, 1 Drawing Sheet
